DESIGN FOR A RACK FOR BREAD OR SIMILAR ARTICLE

Ernest R. Erickson, Des Moines, Iowa, assignor
to C. E. Erickson Company, Incorporated, Des
Moines, Iowa, a corporation of Iowa

Application February 18, 1937, Serial No. 67,725

Term of patent 7 years

To all whom it may concern:

Be it known that I, Ernest R. Erickson, a citizen of the United States, and a resident of Des Moines, in the county of Polk and State of Iowa, have invented a certain new, original, and ornamental Design for a Rack for Bread or Similar Article, of which the following is a specification, reference being had to the accompanying drawing, forming part thereof.

Figure 1 is a perspective view of a rack for bread or similar article illustrating my design.

Figure 2 is an end elevation of the rack, the left edge being shown in section; and

Figure 3 is a front elevation of the same on a reduced scale.

I claim:

The ornamental design for a rack for bread or similar article substantially as shown and described.

ERNEST R. ERICKSON.
